UNITED STATES PATENT OFFICE.

HIRAM M. PRATER AND HENRY R. WILHELM, OF CROCKER, MISSOURI.

STREET-CAR FENDER.

No. 889,151.

Specification of Letters Patent.

Patented May 26, 1908.

Application filed August 29, 1907. Serial No. 390,648.

To all whom it may concern:

Be it known that we, HIRAM M. PRATER and HENRY R. WILHELM, citizens of the United States, residing at Crocker, in the county of Pulaski, State of Missouri, have invented certain new and useful Improvements in Street-Car Fenders; and we do hereby declare the following to be a full, clear, and exact description of the invention, 10 such as will enable others skilled in the art to which it appertains to make and use the same.

The present invention has reference to fenders, and it aims to provide an exceedingly simple and efficient device of that nature which may be readily attached to any street railway car of the ordinary type, and which includes a movable section adapted to be automatically projected forwards when a body in the path of the car is struck thereby, thus forming a cradle into which the body falls.

With the above and other ends in view the invention consists in the particular construction, combination, and arrangement of parts, all as hereinafter fully described, specifically claimed, and illustrated in the accompanying drawings, in which like parts are designated by corresponding reference characters through 30 out the several views.

Of the said drawings, Figure 1 is a side elevation of the fender in contracted condition, and applied to the front end of a car, Fig. 2 is a similar view of the fender extended, Fig. 3 is a plan view of Fig. 2, Fig. 4 is a transverse section through Fig. 1, Fig. 5 is a longitudinal section through Fig. 4, and Fig. 6 is an enlarged detail view of the trigger.

40 In its practical embodiment the fender comprises a body portion or main section 7, whose U-shaped frame is secured at its free ends to the front platform of the car 8, a movable section 9, which telescopes within the main section, and a yielding buffer section 10 which is pivoted to the main section. The last-mentioned section, whose frame is likewise U-shaped and is constructed of a single metal rod, is covered by a wire netting, as 45 shown, the interlaced strands of which are connected to the arms 11 of said frame, the bight portion 12 thereof, and the twisted wire strip 13 which connects the free ends of said arms, which latter are further connected 50 with each other intermediate their ends by a cross-rod 14. The arms 15 of the frame of

the main section 7, which is likewise constructed from a single strip of metal, are each provided with a U-shaped metal plate 16 whose flanges extend inwardly towards the center of the frame the upper flange of each plate having a pair of ears formed thereon towards its forward end between which the free end of the corresponding arm 11 is pivotally engaged. The arms of the main frame 65 are, in turn, connected together by a cross-rod 17 which carries at each end a spring 18 coiled therearound, the free inner end of each spring bearing against the corresponding arm of a trigger 19. This trigger which is W- shaped, as shown, comprises a pair of arms 20 which are connected at their outer ends to the rod 14 and are coiled at their inner ends around the rod 17, and form a central portion or finger 21, the forward end of which is 75 bent to form a hook 22. Owing to the provision of the springs 18, the finger portion of the trigger will be normally forced upwards into position for engagement with the rear end-bar 23 of the movable frame 9, which 80 end-bar is connected with the front end-bar 24 by a series of curved rods 25, the bight portion 26 of the main frame being provided with a series of perforations through which the rods extend. The outermost rods 25 are 85 slidable within the U-shaped metal plates 16, while the central rod 25 carries a retractile coil-spring 27 which is connected at opposite ends to the end-bar 23 and the bight portion 26 of the main frame, the tension of said 90 spring normally forcing the movable section 9, outwards. The arms 11 of the buffer section 10 terminate at their rear ends in depending fingers 28 which are disposed adjacent the corresponding arms 15 of the main 95 section 7, which section is further connected with the platform 8 of the car by a pair of braces 29.

In the operation of the device, the movable section is forced rearwardly, or telescoped, 100 within the main section, against the action of the spring 27, until the rear end-bar is engaged by the hooked portion 22 of the finger 21 whereupon the movable section will be 105 retained in such position. When, however, a person in the path of the car is struck by the fender, he will be toppled thereinto and will fall directly upon the buffer section 10, which section, will, in consequence, be depressed, thus swinging the trigger downwardly against the action of the coil-springs 110 18. The hook portion of the trigger will

thus be disengaged from the end-bar 23 of the movable frame, whereupon the latter will be immediately projected forward under the action of the spring 27, forming, with the 5 main section, a cradle, in which the person is retained, as will be understood.

The operation and advantages of the invention are thought to be apparent from the foregoing, and further description is accordingly deemed unnecessary.

The front end bar 24 of the movable section 9 of the fender is preferably provided with cushions or sleeves of rubber or other yielding material.

15 What is claimed, is,

1. The combination, in a fender of a main section, including a **U**-shaped frame having its bight portion provided with a series of perforations; a movable section adapted to 20 telescope with the main section, and consisting of front and rear end-bars and a series of connecting rods, said rods being slideable through said perforations; means for normally holding said movable section in projected position; means for engagement with said section, when the latter is retracted against the action of said first-mentioned means; and a buffer section pivoted at its 25 forward end to the main section and adapted, when depressed, to release said last-mentioned means from engagement with said end-bar.

2. The combination, in a fender of a main section, including a **U**-shaped frame having 30 its bight portion provided with a series of perforations; a movable section adapted to telescope with the main section, and consisting of front and rear end-bars and a series of connecting rods, said rods being slideable 35 through said perforations; means for normally holding said movable section in projected position; means for engagement with said section, when the latter is retracted against the action of said first-mentioned 40 means; a **U**-shaped plate secured to each arm of the main frame, each of said plates being provided at its upper forward end with a pair of ears; and a buffer section comprising 45 a **U**-shaped frame and a covering of netting secured thereto, the free ends of the arms of said frame being pivotally engaged with said ears, said buffer section being adapted, when depressed, to release said 50 last-mentioned means from engagement with said end-bar.

3. The combination, in a fender, of a main

section; a section adapted to telescope therewith and consisting of front and rear end-bars and a series of rods; means for normally holding said telescoping section in extended position; a swinging trigger carried by the main section and adapted to automatically engage the rear end-bar of the telescoping section when the latter is retracted against the action of said means; and 60 a depressible member pivoted to the main section and adapted, upon actuation, to release said trigger from engagement with said end-bar.

4. The combination, in a fender, of a main 70 section; a section adapted to telescope therewith and consisting of front and rear end-bars and a series of connecting rods; means for normally holding said telescoping section in extended position; a spring-pressed **W**- 75 shaped trigger pivotally connected with the main frame and including a hooked finger adapted, upon actuation, to release said trigger from engagement with said end bar.

5. The combination, in a fender, of a **U**- 80 shaped main frame adapted to be connected to the platform of a car and having its bight portion provided with a series of perforations; a section adapted to telescope therewith and comprising front and rear end-bars 85 and a series of connecting rods, said rods being slideable through said perforations; means connected with the main section and telescoping section for holding the latter normally in projected position; a cross-rod connecting the arms of the main section; a **W**- 90 shaped trigger pivoted upon said cross-rod, and including a hooked central finger adapted for engagement with the rear end-bar of the telescoping section when the latter is retracted against the action of said means; a coil-spring located upon each end of said cross-rod and adapted to bear against the adjacent arm of said trigger to hold the latter in operative position; and a buffer section 95 pivoted at its forward ends to the main section and connected with the arms of said trigger, said buffer being adapted, upon depression to release the trigger finger from engagement with said end-bar.

100 In testimony whereof, we affix our signatures, in presence of two witnesses.

105 HIRAM M. PRATER.
HENRY R. WILHELM.
